UNITED STATES PATENT OFFICE.

HARRY P. NISSEN, OF OAKLAND, CALIFORNIA.

SLEEVE-HOLDER FASTENER.

Application filed March 18, 1926. Serial No. 94,439.

This invention relates to sleeve holders and particularly pertains to a fastener for a sleeve holding device employed in yieldably retaining the cuff of the sleeve in any 5 desired position on the arm, which device is described and claimed in my co-pending application entitled sleeve holder, filed November 3, 1925, Ser. No. 66,445.

This prior device comprises an elastic 10 member having hook means at opposite ends for detachably connecting it to the opposite halves of the snap type of cuff buttons. When the cuff is in use, the device is concealed within the cuff and does not interfere 15 with the operation of the buttons. When the cuff is opened and folded back upon the sleeve, the elastic member is placed under tension so that the cuff will yieldably grip the arm to hold the cuff and sleeve 20 in any desired position thereon. In this manner the cuff may be raised and retained above the elbow without rolling the sleeve.

It is the principal object of the present 25 invention to provide a generally improved fastener for devices of the character referred to which fastener is simple and inexpensive to manufacture, and will adapt itself for use in connection with cuff buttons of various different sizes.

30 One form which the invention may assume is exemplified in the following description and illustrated by way of example in the accompanying drawings, in which:

Fig. 1 is a view of a sleeve holder with 35 my improved fastener applied thereto.

Fig. 2 is a view of the fastener when blanked from a sheet of metal.

Fig. 3 is an enlarged view of the fastener 40 disclosing the manner in which it engages a cuff button.

Referring more particularly to the accompanying drawings, 10 indicates a sleeve holder comprising a strip of elastic material 11 having fasteners 12 disposed at opposite ends. This sleeve holder is particularly adapted for use in connection with the snap type of cuff buttons, which are made in halves having male and female means for frictionally connecting them. 45 Each half of this type of cuff button is formed of a pair of spaced collars joined by a round shank, which is smaller in diameter than the collars. It is to these halves of the button that the fasteners 12 are adapted to connect.

When the cuff of a sleeve is disposed in normal position with the cuff button halves connected and with the fasteners 12 engaged with the button, the elastic portion 11 of the device will be concealed within the 60 cuff. When it is desired to raise the cuff on the arm for any reason, the cuff button halves are disconnected and the cuff is folded back upon the sleeve. This is accomplished without disengaging the sleeve holding device 65 10 from the opposite halves of the cuff button.

When the cuff is folded over the sleeve, the elastic portion 11 of the device will be placed under tension so that the cuff will 70 yieldably grip the arm. It is with the construction of the fasteners 12 that the present application is particularly concerned.

The fasteners 12 are formed from sheets of material by die-stamping or otherwise. 75 The material used may be of any spring material, but I prefer, however, to use German silver.

Each fastener is formed with a hook portion 14 having a semi-circular recess 15 for 80 engaging the shank 16 of a button. The hook portion 14 extends outwardly from the body portion 17 of the fastener. Arranged adjacent the hook portion is a spring finger 18 which is integrally connected as at 19 to 85 the side of the fastener opposite the hook. This spring finger 18 is arcuate and extends to a point closely adjacent to the inner corner of the semi-circular recess 15 of the hook.

The material between the spring finger 90 and the body portion 17 is cut-away to form a recess 20, so that the spring finger may move toward the body portion. The free end of the spring finger 18 terminates short of the recess 15 and slightly toward its center, so as to obstruct to a certain extent the throat of the hook. When the fastener is 95 engaged with the cylindrical shank 16 of the cuff button, the free end of the spring finger 18 is moved inwardly toward the body portion 17, as shown in dotted lines in Fig. 3, and its end will engage the periphery of the shank 16 at a point beyond its center, thereby yieldably retaining the fastener in place on the button.

To connect the fastener to the strip of elastic material, the body portion 17 thereof is formed with tabs 21 which extend from opposite sides of the body portion. When the fastener is to be connected with the elastic 110

strip, these tabs 21 are bent over upon the body portion 17 and clamped to the elastic strip, as shown in Figs. 1 and 3.

From the foregoing it is obvious that I have provided a very simple and inexpensive fastener for sleeve holders, which may be manufactured in quantities at an extremely low cost, and which will act efficiently in connecting a sleeve holder to a cuff button.

10 While I have shown the preferred form of my invention, it is to be understood that various changes may be made in its construction by those skilled in the art without departing from the spirit of the invention, as 15 defined in the appended claims.

Having thus described my invention, what I claim and desire to secure by Letters Patent is:

1. A fastener for sleeve holders comprising a body portion having means at one end for connecting it to an elastic strip, a hook projecting from the opposite end of the body portion and located at one side thereof, said hook having a semi-circular recess for receiving the shank of a cuff button, said hook being arranged at an angle to the longitudinal center line of the body portion, a spring finger integrally connected at one end to the side of the body portion opposite the hook 25 and at the same end of the body portion as the hook, said spring finger extending transversely to a point short of the inner side of the recess of the hook and partly obstructing the same.

35 2. A fastener for sleeve holders comprising a body portion having means at one end

for connecting it to an elastic strip, a hook projecting from the opposite end of the body portion at one side thereof, said hook being arranged at an angle to the longitudinal center of the body portion, a spring finger formed integral with the body portion at the side thereof opposite the hook and at the same end as the hook, said spring finger being formed slightly arcuate and extending 45 substantially transversely of the body portion at a spaced distance therefrom, the free end of said hook terminating short of the inner edge of the recess and partly obstructing said recess. 50

3. A fastener for sleeve holders comprising a body portion having a hook projecting from one end thereof, said hook being arranged at an angle to the longitudinal center of the body portion, a spring finger 55 formed integral with the body portion at the side thereof opposite the hook and at the same end as the hook, said spring finger being formed slightly arcuate and extending substantially transversely of the body portion at a spaced distance therefrom, the free end of said hook terminating short of the inner edge of the recess and partly obstructing said recess, means at the opposite end of the body portion for connecting the fastener to 60 an elastic strip, said means comprising tabs formed integral with the body portion and extending outwardly from opposite sides thereof, said tabs being adapted to be bent upon the body portion to clamp the same to 65 the elastic strip. 70

HARRY P. NISSEN.
